(57) **CLAIM**

The ornamental design for a basket filter, as shown and described.

DESCRIPTION

FIG. 1 is a side elevation view of a basket filter.

1 Claim, 11 Drawing Sheets

FIG. 2 is a side elevation view of a basket filter rotated 90-degrees from FIG. 1.

FIG. 3 is a top view of a basket filter (the bottom view being identical).

FIG. 4 is a side isometric view of a basket filter showing my new design.

FIG. 5 is an exploded side view of the upper portion of a basket filter.

FIG. 6 is an exploded side view of the middle portion of a basket filter.

FIG. 7 is an exploded side view of the lower portion of a basket filter.

FIG. 8 is an end view taken in the direction of line VIII in FIG. 5.

FIG. 9 is an end view taken in the direction of line IX in FIG. 5.

FIG. 10 is an end view taken in the direction of line X in FIG. 5.

FIG. 11 is an end view taken in the direction of line XI in FIG. 6.

FIG. 12 is an end view taken in the direction of line XII in FIG. 6.

FIG. 13 is an end view taken in the direction of line XIII in FIG. 7; and,

FIG. 14 is an exploded side isometric view of a basket filter showing clearly the internal design features.
